UNITED STATES PATENT OFFICE.

ALBERT A. ARNOLD, OF CHICAGO, ILLINOIS.

BOX-COVER.

1,085,188.

Specification of Letters Patent.

Patented Jan. 27, 1914.

Application filed June 9, 1913. Serial No. 772,524.

To all whom it may concern:

Be it known that I, ALBERT A. ARNOLD, citizen of the United States, residing at Chicago, in the county of Cook and State of Illinois, have invented certain new and useful Improvements in Box-Covers, of which the following is a specification.

This invention relates to the construction of boxes made from card-board or other suitable similar material, and especially to that type of such boxes designed to be manufactured, sold and shipped and stored in "the flat" or "knock-down" arrangement, and adapted to be folded or brought into usable form by the purchasers.

The especial object of my present invention is to provide a box or box cover of the style mentioned that will be cheap to manufacture in that there are no hand operations required, and but little waste of material, and that when folded or set up, will effectively maintain its completed form under all ordinary conditions to which it may be subjected.

A further object is to provide a box or box-cover in which rests or supports will be provided to receive the complementary receptacle or member in such manner as to facilitate the display of the contents of the box.

Other objects of general utility are conserved by my invention as will be readily apparent to those skilled in the art to which it appertains.

I have shown my invention as applied to a box-cover, but the same construction may be used in making the boxes, if desired.

Figure 1 is a perspective view of a box-cover in its partially assembled or folded condition; Fig. 2 is a plan view of the blank from which the cover shown in Fig. 1 is made.

Referring to the details of Fig. 2, the reference character 3 represents the central portion of the rectangular blank of card-board or other suitable material, the outlines of same being defined or bounded by the dotted lines 3^a, 3^b, which indicate the lines along which the blank is scored or creased to facilitate the subsequent folding operations.

4, 4, represent the sections adjacent the long sides of section 3, and 5, 5, the sections along the outer margins of and are shorter than the portions 4—4, scored lines 4^a, 4^b, being run between said sections 4 and 5. The sections 5, have square pieces cut from

their corners so as to leave right angled notches 5^a. The sections 4 are scored transversely near their ends, as indicated by dotted lines 4^c, and the blank is cut through along the lines 4^d, thus leaving end sections 4^b which are adapted to be bent inwardly when the blank is folded into box form, as indicated at the right-hand side of Fig. 1.

The transverse scores indicated by dotted lines 3^b, are between the center portion 3, and end sections 6, the latter forming, with the flaps 4^b, the ends of the box when folded at right-angles to section 3. The sections 6 are defined by scores indicated by the dotted lines 6^a, which provide folding lines for the sections 7 which are parallel to the sections 6, and are provided at their corners with wings 7^b which extend beyond the margins of the portions 7, and are formed by cuts 7^a and creases or scores 7^c, the latter facilitating the bending outwardly of the wings as shown in Fig. 1.

A blank of the form shown, and cut and scored as described is preferably finished by pasting the sections 5 to the sections 4, thus bringing the long edges of the sections 5, adjacent the scored lines 3^a, but this operation is not essential to the construction of the complete article. Assuming that the blanks are furnished the user with the sections 5 pasted over the sections 4, the latter will bend up the blank along the lines 3^a, and bend inwardly the flaps 4^b at right-angles to the sides 4—5. The end sections 6 will then be bent upwardly at right-angles to the section 3, and the sections 7 will be bent over the flaps 4^b thus bringing the section 7 on the inside of the structure. The wings 7^b will then be pressed into the angular recesses formed by the notches 5^a, so that the edges of the wings will engage the edges of the members 5 on two sides of said notches with sufficient tension (incident to the material) to hold them in place. It will be obvious that with these wings extending angularly across the four corners of the structure, they will not only hold the sections 7 in place, but will afford rests upon which the bottom of the body of the box may rest when inverted to display the contents, as well as spacers which will maintain the cover and box in proper relative position when the box is closed.

I have not shown a box body adapted to fit within the cover described, as it may be of any desired construction, or may be made in

accordance with my invention covered by a separate application for Letters Patent.

Having thus described my invention, what I claim as new and desire to secure by Letters Patent, is:—

A box member composed of suitable material, cut, scored and folded to provide a bottom wall, double side walls and double end walls, the inner members of the side walls having rectangular recesses at the lower corners of the structure, and the inner

members of the end walls having wings adapted to extend diagonally across the lower corners of the structure and to engage the edges of the side members adjacent said recesses.

In testimony whereof I affix my signature in the presence of two witnesses.

ALBERT A. ARNOLD.

Witnesses:

W.M. HAROLD EICHELMAN,
M. A. MILDRED.
